UNITED STATES PATENT OFFICE.

THOMAS A. BRIGGS, OF ARLINGTON, MASSACHUSETTS, ASSIGNOR TO THE BRIGGS MANUFACTURING COMPANY, OF NIAGARA FALLS, NEW YORK.

APPARATUS FOR TRANSFERRING PAPER FROM FEEDING-MACHINES TO PRINTING-PRESSES.

SPECIFICATION forming part of Letters Patent No. 557,761, dated April 7, 1896.

Application filed February 2, 1893. Renewed May 29, 1895. Serial No. 551,227. (No model.)

To all whom it may concern:

Be it known that I, THOMAS A. BRIGGS, of Arlington, in the county of Middlesex, in the State of Massachusetts, have invented new and useful Improvements in Apparatus for Transferring Paper from a Feeding-Machine to a Printing-Press, of which the following, taken in connection with the accompanying drawings, is a full, clear, and exact description.

The purpose of this invention is to provide simple and efficient means for transferring paper from a feeding-machine to the feed-table of a printing-press situated remote from said machine; and to that end the invention consists, essentially, in the combination, with said machine and press, of a fly, interposed between the same, and grippers moving lengthwise of the fly and transferring the paper from the feeding-machine onto the fly; and the invention also consists in certain novel features of the details of the paper-transferring devices, and means for actuating the same, as herein-after fully described, and specifically set forth in the claims.

In the accompanying drawings, Figure 1 is a side elevation of a paper-transferring apparatus embodying my invention. Fig. 2 is a plan view of the same. Fig. 3 is a vertical transverse section on line xx in Fig. 2. Fig. 4 is an enlarged detached side view of the cam-disk which imparts motion to the fly and grippers in moving lengthwise of the fly. Fig. 5 is a detached side view of mechanism which transmits motion from the aforesaid cam-disk to the rock-arm, by means of which the grippers are moved lengthwise of the fly. Fig. 6 is an enlarged front view of one of the grippers. Fig. 7 is a vertical transverse section of the same. Fig. 8 is a side view of one of said grippers, showing its position in relation to the fly in carrying the paper over the same. Fig. 9 is an enlarged side view of the device for cushioning the fly at the end of its stroke, and Fig. 10 is a plan view of the same.

Similar letters of reference indicate corresponding parts.

A denotes a paper-feeding machine, which feeds the sheets of paper singly from a pile supported on a table A' . The mechanism for feeding said paper may be of any suitable

and well-known construction, and for exemplification I have merely indicated by dotted lines in Fig. 9 of the drawings one of the feeding-fingers of the machine shown and described in my United States Letters Patent No. 480,447, dated August 9, 1892.

B represents the impression-cylinder of a printing-press, and B' the usual feed-table, upon which the paper is placed preparatory to passing the same to the printing-press. The paper-feeding machine is arranged remote from said feed-table, and in order to economize in room and render the combined feeding-machine, printing-press, and paper-transferring devices as compact as possible I place the feeding-machine A over the end of the printing-press, as shown in Fig. 1 of the drawings.

From the printing-press frame, adjacent to the impression-cylinder B, to the delivery end of the feeding-machine A, I extend two parallel rectilineal guides C C, firmly secured thereto. Upon these guides, adjacent to the impression-cylinder, I mount the pedestals D, to the bases of which I pivot the shaft F' of the fly F, which is adapted to swing with its free end back and forth to and from the paper-feeding machine A and feed-table B'. This fly receives its motion by the following mechanism: To the end of the fly-shaft F' is fastened a gear-wheel G, with which meshes a segmental gear G', pivoted to the upper end of the pedestal D, which latter gear receives an oscillatory motion from a revolving cam-disk H on the side of the frame of the feeding-machine A by means of the pitman I, one end of which is connected to the segmental gear by a bolt passing through a longitudinal slot e in said gear. Said slot allows the pitman to be connected at a greater or less distance from the axis of the gear, and thus vary the thrust of the fly as may be desired. The opposite end of the pitman is formed with a longitudinal slot I', receiving through it the hub of the cam-disk H, so as to support said end of the pitman. On the end of the pitman is pivoted a roller I'', which travels in the groove H' of the cam-disk.

In order to properly time the movement of the fly so as to swing with desired speed back and forth between the feeding-machine and

printing-press and hold it dormant a sufficient length of time to allow the paper to be transferred onto it from the feeding-machine A, a portion of the cam-groove H' is formed 5 concentric to the axis of the disk, and the remainder of said groove being in two short curves extending from the ends of the concentric portion and meeting in proximity to the opposite side of the axis of the disk, as 10 shown in Fig. 4 of the drawings.

Upon the guides C C, I mount the slides L L, on which are supported the ends of the shaft a, which is parallel with the axis of the fly, and to this shaft I fasten the gripper- 15 arms b, as shown in Figs. 6 and 7 of the drawings. This arm is provided with a vertically-movable stem b', to the upper end of which is secured the gripper finger or jaw b''. To the lower portion of said stem is attached the 20 foot d, and between the top of the foot and a bearing in the upper portion of the arm b is a spiral spring d', which depresses the stem and thereby holds the gripper normally closed.

For opening and closing the grippers at opposite ends of the strokes of the fly I pivot to 25 the slides L L another shaft a', which passes through eyes in horizontal projections on the bases of the gripper-arms b, and thus sustains said arms in their erect positions. To the 30 shaft a' are fastened the cams d'', which bear on the under side of the feet d.

To one end of the shaft a' is firmly secured the tripping-finger a'', which at the end of each stroke of the fly comes in contact with 35 one of the two stops c c, attached to opposite ends of the guide C. The contact with the stop c, near the heel of the fly, turns the shaft a', so as to cause the cams d'' to pry up the feet d of the grippers b'' and thus release the 40 sheet to allow it to be taken by the usual grippers of the impression-cylinder B. In this operation of opening the grippers b'' the cams d'' are turned past a vertical position and become partially locked under the feet 45 d to maintain the grippers in their open position during the reverse movement of the slides L L, by which the said grippers are caused to approach the paper-feeding machine. At the end of this movement the contact of the tripping-finger a'' with the stop c 50 turns back the shaft a', and thus causes the cams d'' to release the grippers to take hold of the advance edge of the sheet delivered thereto by the feeding-machine.

55 The slides L L receive longitudinal motion on the guides C C by means of the rock-arm N, which is pivoted to the frame of the feeding-machine A and connected at one end to the slide L by a pitman O. The opposite end 60 of said rock-arm is pivoted to the free end of a lever P, which is pivoted to the aforesaid frame and is provided with a longitudinal groove, in which travels a roller f, pivoted to the back of the cam-disk H, the rotation of 65 which imparts an oscillatory motion to the lever P.

In order to enable the rock-arm N to move

the slide L the entire length of the guide C, I apply to said rock-arm the mechanism shown in my United States Letters Patent No. 70 480,449, dated August 9, 1892, said mechanism consisting, essentially, of a shaft extending lengthwise of the rock-arm and journaled thereon. A pinion on the inner end of said shaft, meshing with a stationary gear on the 75 frame of the machine, imparts rotary motion to the shaft during the oscillation of the rock-arm. A miter-pinion on the outer end of said shaft meshes with a similar pinion on a short shaft pivoted crosswise to the free end 80 of the rock-arm, and an arm fixed at one end to said short shaft has connected to its opposite end the pitman O.

R represents a cushion which is sustained in a position to receive the impact of the free 85 end of the fly at the end of its stroke toward the feeding-machine. This cushion I form of a rubber tube g, a portion of the circumference of which is inserted into a tubular bar h, which is provided with a longitudinal 90 slot, through which a portion of the circumference of the tube protrudes, as shown in Figs. 9 and 10 of the drawings.

The rubber tube is secured in the bar by means of a plug h' driven into the inclosed 95 portion of the tube. For sustaining said cushion in its position I prefer to employ a horizontal shaft i, fastened to the frame of the feeding-machine A and having secured to it the arm j, the free end of which is formed 100 with the tubular and longitudinally-slotted bar or cross-head h, within which the rubber tube g is secured in the manner aforesaid.

Having described my invention, what I claim as new, and desire to secure by Letters 105 Patent, is—

1. In combination with a printing-press and paper-feeding machine, a fly interposed and pivoted adjacent to the press, guides extending lengthwise of the fly, slides on said guides, 110 a shaft extending across the fly and connected to the slides, and grippers attached to said shaft to transfer the paper from the feeding-machine to the fly, as set forth.

2. In combination with the printing-press 115 and paper-feeding machine, a fly pivoted adjacent to the press and swinging to and from the said machine and press, guides extending lengthwise of the fly, slides mounted on said guides, a shaft extending across the fly 120 and connected to the slides, grippers connected to said shaft, and stops at opposite ends of the guides and tripping the grippers, as set forth.

3. In combination with a printing-press and 125 paper-feeding machine, rectilineal guides extending from the press to said machine, a fly mounted on said guides adjacent to the press, slides mounted on said guides, a shaft parallel with the axis of the fly, grippers attached 130 to said shaft, stops on opposite ends of the guides tripping the grippers, a rock-arm imparting motion to the slides, a cam actuating the rock-arm, gears actuating the fly, and a

pitman transmitting motion from the aforesaid cam to the said gears, as set forth.

4. In combination with the printing-press and paper-feeding machine, a fly interposed between said press and machine, and pivoted adjacent to the press, paper-feeding fingers depositing the sheet upon the fly, a gear-wheel attached to the fly-shaft, a segmental gear meshing with said wheel, a pitman connected to said segmental gear adjustably in its distance from the axis thereof, and a revolving cam imparting motion to the pitman as set forth.

5. In combination with the printing-press and paper-feeding machine, rectilineal guides extending from the press to said machine, a fly having its shaft mounted on said guides adjacent to the press, a gear-wheel attached to the fly-shaft, a segmental gear meshing with said gear-wheel, slides mounted on the guides, a shaft parallel with the axis of the fly and connected to the slides, grippers attached to said shaft, stops on opposite ends of the guides and tripping the grippers, a revolving disk provided with a continuous cam-groove, a portion of which is concentric to the axis of the disk and the remainder of said groove being in two short curves extending from the ends of concentric portion and meeting in proximity to the opposite side of the axis of the disk, a pitman connected at one end to the aforesaid segmental gear and provided at the opposite end with a longitudinal slot and riding thereby on the hub of the cam-disk and having pivoted to it a roller traveling in the cam-groove, a lever pivoted to the frame and receiving oscillatory motion from

the aforesaid cam-disk, a rock-arm having one of its free ends pivoted to the said lever, and a pitman connecting the opposite end of the rock-arm to one of the aforesaid slides, substantially as described and shown.

6. In combination with the rectilineal guides, slides mounted thereon and stops *c c* attached to opposite ends of the guides, the shaft *a* mounted on the slides, the gripper-arm *b* fastened to said shaft, the stem *b'* movable longitudinally on said arm, the gripper-finger *b''* and foot *d* attached to said stem, the spring *d'* depressing the stem, the shaft *a'* pivoted to the slides and passing through projection on the base of the arm, the cam *d''* attached to said shaft, and the tripping-finger *a''* attached to the shaft in position to come in contact with the aforesaid stops at the ends of the strokes of the slides, as set forth.

7. In combination with the paper-feeding machine and the fly swinging to and from said machine, a shaft fixed horizontally to the frame of said machine, arms extending from said shaft toward the fly and terminating with tubular and longitudinally-slotted cross-heads, rubber tubes inserted in said cross-heads and protruding through the slots thereof, and plugs inserted in the inclosed portions of the rubber tubes and fastening the same in the cross-heads, as set forth and shown.

In testimony whereof I have hereunto signed my name this 18th day of January, 1893.

THOMAS A. BRIGGS. [L. S.]
